PUNCHING DEVICE

Marie Ahlenius, Chicago, Ill., assignor of one-third to Maurice H. Herman, Chicago, Ill.

Application April 17, 1935, Serial No. 16,878

9 Claims. (Cl. 164—119)

My invention relates to a punching device of the class for punching an air intake and a discharge opening in a can to permit pouring therefrom of its contents.

My invention has for its object to provide, in a manner as hereinafter set forth, a punching device enabling the punching selectively or simultaneously in a safe, easy and expeditious manner, of an air intake and discharge opening in a can whereby the necessity is obviated of one's being forced to resort to the expedient of hammering a sharp nail, knife or other sharp implement for the purpose, the use of such latter mentioned devices oftentimes resulting in injury to the hand due to the slipping of the nail, knife or implement used.

My invention has for its further object to provide, in a manner as hereinafter set forth, a punching device for selectively or simultaneously punching in a can an air intake and a discharge opening of like area or with the intake of less area than the discharge opening.

A further object of my invention is to provide, in a manner as hereinafter set forth, a punching device for the purpose set forth for simultaneously punching in a can an air intake and a discharge opening in parallel spaced relation and for selectively positioning by separate means the intake and discharge openings at different distances apart.

Further objects of my invention are to provide, in a manner as hereinafter set forth, a punching device for the purpose referred to which is simple in its construction and arrangement, strong, durable, compact, thoroughly efficient in its use, conveniently operated and inexpensive to manufacture.

With the foregoing and other objects in view, my invention consists of such parts and such combination of parts as are hereinafter more specifically described and as illustrated in the accompanying drawing, wherein is shown an embodiment of my invention, but it is to be understood that changes, variations and modifications may be resorted to which fall within the scope of the invention as claimed.

In the drawing:

Figure 1 is a side elevation of the device.

Figure 2 is a top plan view.

Figures 3 and 4 are sectional views respectively on lines 3—3 and 4—4, Figure 1.

Figure 5 is a top plan view of a can top punched by the device to provide it with an air intake and a discharge opening of like area, and

Figure 6 is a fragmentary view in top plan of

a can top punched by the device to provide it with a discharge opening of enlarged area.

The device includes a carrier 7 for two pairs of oppositely disposed punches to be referred to. The carrier 7 is of bar like form and it consists of central rectangular part 8, a pair of rectangular hollow parts 9, 10 open at their tops and bottoms and constituting housings, a pair of oblong parts 11, 12 and a pair of oppositely disposed tapered end parts 13, 14.

The housings formed by the parts 9, 10 are of like form and each includes an inner end wall 15, an outer end wall 16 and a pair of spaced parallel side walls 17, 18. The walls 15, 16, 17 and 18 of the housings coact to provide rectangular chambers 19, 20 open at their upper and lower ends. The ends of the central part 8 merge into and at the vertical medians of the end walls 15 of the housings. The inner sides of the parts 11 and 12 merge with and at the vertical medians of the outer end walls 16 of the housings. The outer sides of the parts 11 and 12 merge into the inner ends of the parts 13, 14 respectively. The side walls of the housings are outset with respect to the parts 8, 11 and 12 of the carrier 7. Secured upon the parts 13, 14 are oppositely extending handle members 21, 22 respectively.

Arranged in and disposed lengthwise of the chamber 19 is an S-shaped body 23 common to a pair of oppositely extending punches 24, 25 of like form. Each punch is of rectangular contour in transverse cross section and is formed of a shank 26 terminating in a puncher or piercer 27 of tapered contour. The shanks and punchers or piercers of the punches 24, 25 are of like form and size. The body 23 includes a pair of oppositely disposed U-shaped bends 28, 29. The bend 28 opens in a direction towards the top and the bend 29 opens in a direction towards the bottom of chamber 19. The outer edge of bend 28 is flush with the lower edges and the outer edge of bend 29 is flush with the upper edges of the side walls of chamber 19. The outer end of body 23 is at the top edges and the inner end of the body 23 is at the bottom edges of the side walls of chamber 19. The shank 26 of punch 24 merges into the outer end of body 23. The shank 26 of punch 25 merges into the inner end of body 23. Extending transversely of the part 9 of carrier 7 is a pair of spaced parallel rivets 30, 31 having their ends upset and bearing against the outer faces of the side walls of chamber 19. The rivets 30, 31 bear against the inner edges of the bends 28, 29 respectively. The rivets function to anchor body 23 to part 9 and to prevent lon-

gitudinal and vertical shifting of body 23 with respect to chamber 19.

Arranged within and disposed lengthwise of the chamber 20 is an S-shaped body 32 common to a pair of oppositely extending punches 33, 34 provided with shanks 35, 36 of rectangular cross section. Integral with the shank and forming a part of punch 33, 35 is a tapered puncher or piercer 37 of rectangular cross section and of the same size as the puncher or piercer 27 of the punch 24. The shank 36, at its outer end, is headed, as at 38, and has mounted thereon between head 38 and the top edges of the side walls of the chamber 20, as well as bearing against said edges and head, a hollow puncher or piercer member 39 of substantially right angled contour in side elevation forming a part of punch 34. The vertical leg 40 of member 39 extends beyond the outer end of the inclined leg 41 of member 39. The leg 40 has a cutting edge 42. The leg 41 has side cutting edges 43. The member 39 constitutes a puncher or piercer which is of rectangular contour in plan and is of greater length, breadth and width than that of the puncher 37.

The puncher or piercer of the punch 24 is arranged in parallel relation to the puncher or piercer of the punch 33. The puncher or piercer of punch 25 is arranged in parallel spaced relation to the puncher or piercer of the punch 34, but the distance between the puncher or piercer of the punch 25 and the puncher or piercer 39 is greater than that between the puncher and piercer of the punch 35 and the puncher or piercer 37.

The body 32 includes a pair of oppositely disposed U-shaped bends 44, 45. The bend 44 opens in a direction towards the top and the bend 45 opens in a direction towards the bottom of chamber 20. The outer edge of bend 44 is flush with the upper edges and the outer edge of bend 45 is flush with the bottom edges of the side walls of chamber 20. The inner end of body 32 is at the bottom edges and the outer end of body 32 is at the top edges of the side walls of chamber 20. The shank 35 merges into the inner end of body 32. The shank 36 merges into the outer end of body 32. Extending transversely of portion 19 of carrier 7 is a pair of spaced parallel rivets 46, 47 having their ends upset and bearing against the outer faces of the side walls of chamber 20. The rivets 46, 47 bear against the inner edges of the bends 44, 45 respectively. The rivets 46, 47 function to anchor body 32 to part 9 of carrier 7 and to prevent longitudinal and vertical shifting of body 32 with respect to chamber 20.

The punchers or piercers 27, 35 function to form the top 48 of the can with the rectangular openings indicated at 49. The function of puncher or piercer 39 is to form the top 50 of the can with a rectangular opening 51 of greater area than the openings 49. When the puncher or piercer of the punch 25 is used in connection with the puncher or piercer of the punch 33, and when pressure is applied upon the device, the two punchers or piercers will provide simultaneously in the can top, a pair of diametrically opposed openings, of like form. One will constitute an air intake and the other an outlet or discharge opening for the contents of the can. When the puncher or piercer of the punch 24 is used in connection with the puncher or piercer 39, and when pressure is applied upon the device, 75 these two punchers or piercers will provide simul-

taneously in the can, a pair of diametrically opposed rectangular openings of different area, the smaller of which will constitute an air intake and the larger of which will form an enlarged outlet or discharge opening, thus enabling the 5 contents of the can to be freely poured therefrom.

When the punches 24, 34 are used, the openings 49, 51 respectively provided thereby will be a greater distance apart than the openings 49 provided by the use of the punches 25, 33. The 10 openings 49, 51 are of rectangular shape but with the opening 51 of a size appreciably larger than openings 49.

It is to be understood that the puncher or piercer 37 of the punch 33 may be of the same 15 construction as that of the puncher or piercer 39 of the punch 34.

That portion of one of the lengthwise edges of the carrier between the handle members 21 and 22 constitutes a stop for arresting the punching action of the punches 26, 34 and that portion of the other lengthwise edge of the carrier between the handle members 21 and 22 constitutes a stop for the punching action of the punches 25, 33.

The S-shaped bodies 23 and 32 constitute spaced coupling means for connecting the punches to and in extended relation with respect to the lengthwise edges of the carrier.

The material of the can top which is freed by the puncher or piercer 39 is extended into the can by the action of the puncher or piercer. This prevents any possibility of injury to the hands by reason of handling of the can and contact with rough edges which might otherwise 35 be formed. At the same time, the appearance of the can top is not rendered unsightly but is neat. The said freed portion will permit free and ready pouring of the contents from the can.

What I claim is:

1. A punching device for the purpose set forth comprising a carrier formed with a pair of spaced parallel open top and bottom chambers, an S-shaped body anchored in each of said chambers, and a pair of oppositely disposed punches extending from the ends of each of said bodies.

2. In a punching device for the purpose set forth, a carrier, an S-shaped body anchored thereto, and a pair of oppositely disposed punches extending from the ends of said body.

3. In a punching device, a carrier, a pair of oppositely disposed punches extending from the carrier adjacent the ends of the latter, and a coupling means for said punches, said coupling means being housed completely with and anchored to said carrier and terminating at its ends in said punches.

4. In a punching device, a carrier, a punch including a shank and a puncher or piercer having a piercing edge at its outer end and a piercing edge at each side disposed at an angle to and extending towards the said outer edge, said puncher or piercer being of substantially triangular form, and anchoring means for said shank anchored to said carrier, the piercing edges at the sides of the puncher or piercer being throughout inwardly adjacent of the said piercing edge at the said outer end.

5. In a punching device, a carrier, an S-shaped body formed with oppositely disposed bends, a pair of oppositely disposed punches extending from the ends of said body and each having the outer end portion in the form of a puncher or piercer, and means extending through the bends of said body and said carrier for anchoring the latter and said

40

body together to prevent the latter shifting lengthwise and vertically with respect to the carrier.

- 5 6. In a punching device, a carrier, an S-shaped body formed with oppositely disposed bends, a pair of oppositely disposed punches extending from the ends of said body and each having the outer end portion in the form of a puncher or piercer, and means extending through the bends 10 of said body and said carrier for anchoring the latter and said body together to prevent the latter shifting lengthwise and vertically with respect to the carrier, the puncher or piercer outer end portion of one of the said punches being of 15 greater length and breadth than that of the puncher or piercer outer end portion of the other of said punches.

7. In a punching device for the purpose set forth, a stationary S-shaped body provided at 20 each end with an outwardly extending punch, said punches being disposed in opposite directions.

8. In a punching device for simultaneously forming a pair of spaced parallel openings at 25 selected distances apart, a carrier formed with a pair of vertical chambers between its transverse median and each end thereof, said chambers opening at the lengthwise edges of the carrier, two oppositely disposed pairs of punches, 30 the punches of each pair being disposed in par-

allel spaced relation, the distance between the punches of one pair being greater than that between the punches of the other pair, each pair of punches extending from a lengthwise edge of said carrier, means within the chambers and being anchored at spaced points thereof to the carrier for anchoring the punches stationary with respect to the carrier, and each lengthwise edge of the carrier constituting a stop for arresting the punching action of a pair of punches. 10

9. In a punching device for simultaneously forming a pair of spaced parallel openings at selected distances apart, a carrier formed with a pair of vertical chambers between its transverse median and each end thereof, said chambers 15 opening at the lengthwise edges of the carrier, two oppositely disposed pairs of punches, the punches of each pair being disposed in parallel spaced relation, the distance between the punches of one pair being greater than that between the 20 punches of the other pair, each pair of punches extending from a lengthwise edge of said carrier, a pair of spaced parallel coupling means fixedly secured within the chambers lengthwise of the latter, each of said coupling means at each end 25 thereof merging in a punch, and each lengthwise edge of the carrier constituting a stop for arresting the punching action of a pair of punches.

MARIE AHLENIUS. 30
